Primary Examiner — Sandra S Snapp

Assistant Examiner — Ieisha N Price

(74) Attorney, Agent, or Firm — Brinks Gilson & Lione

(57) **CLAIM**

The ornamental design for a load binder, as shown and described.

DESCRIPTION

FIG. 1 is a perspective view of a load binder showing my new design;

FIG. 2 is front elevation view thereof;

FIG. 3 is a rear elevation view thereof;

FIG. 4 is a left side elevation view thereof;

FIG. 5 a right side elevation view thereof;

FIG. 6 is a top plan view thereof;

FIG. 7 is a bottom plan view thereof; and,

FIG. 8 is a perspective view with the ratchet handle thereof in an alternate position.

The broken lines in the drawings illustrate portions of the load binder and form no part of the claimed design.

1 Claim, 7 Drawing Sheets---
